[57] CLAIM

The ornamental design for a bolt, nut, screw and thread
gage, as shown and described.

DESCRIPTION

FIG. 1 is a top perspective view of a bolt, nut, screw,
and thread gage showing my new design, the bottom,
not shown, being plain and unornamented.

FIG. 2 is one end of the gage shown in FIG. 1.

FIG. 3 is the end opposite to the end shown in FIG. 2.

FIG. 2.

FIG. 1.

FIG. 3.
